APPARATUS FOR CONTROLLING
REFRIGERATING SYSTEMS

Edward F. Dickieson, Jr., Detroit, Mich.; Nathalie L. Dickieson, executrix of said Edward F. Dickieson, Jr., deceased, assignor to Nathalie L. Dickieson

Application February 4, 1949, Serial No. 74,585

7 Claims. (Cl. 62—4)

This invention relates generally to refrigeration and more particularly to a method of and apparatus for the control of a refrigerating system whereby the condensing unit thereof is prevented from becoming overloaded.

An object of this invention is to provide an improved method for operating a refrigerating system.

Another object of this invention is to provide a new controlling means for controlling the flow of vapor to a compressor.

A further object of this invention is to provide such a mechanism with means responsive to the suction pressure of the compressor.

A further object of this invention is to provide such a means which is responsive to discharge pressure of the compressor.

A further object of this invention is to provide a novel control system having the aforesaid characteristics and the control of which is additionally modified in accordance with conditions contained with the space to be refrigerated.

Other objects will be apparent from the specification, the claims appended thereto and the drawings in which drawings

Figure 1 is a diagrammatic view of a refrigerating system embodying the invention;

Fig. 2 is a view in partial central vertical section of a control element embodying the invention which may be utilized in the system of Fig. 1, the device being connected between the outlet of the evaporator and the inlet of the compressor;

Fig. 3 is a view in central vertical section of a modified form of the control element shown in Fig. 2;

Fig. 4 is a schematic view of a refrigerating system embodying a modified form of the invention;

Fig. 5 is a view similar to Fig. 3 showing the manner in which the apparatus of Fig. 3 may be modified to accommodate itself for use in the refrigerating system shown in Fig. 4;

Fig. 6 is a view in central vertical section of a control mechanism used in the system of Fig. 4 the device being connected between the receiver and the compressor inlet and in open communication with the evaporator;

Fig. 7 is a diagrammatic view of a still further modified form of refrigerating systems embodying the invention; and

Fig. 8 is a view in central vertical section of a control element for actuating the throttle of a governor-controlled gasoline engine in the system of Fig. 7, the control element of this figure being employed to vary the setting of the governor over a definite range of engine speeds, the control device of Fig. 6 being used to further vary the compressor capacity when necessary in accordance with the demands of the space refrigerated.

Referring to the drawings by characters of reference, 1 indicates generally a compressor having its discharge outlet connected by means of a conduit 2 to a condenser 3 wherein the gaseous refrigerant pumped by the compressor 1 is condensed to a liquid in the usual manner.

2

A receiver tank 4 receives the condensed liquid from the condenser 3. Liquid refrigerant flows from the tank 4 through a conduit 6 under control of a thermostatic expansion valve 8 to an evaporator 10 located within a space 12 which is to be cooled. The evaporator 10 is connected by means of a suitable conduit 14 to the inlet 16, Fig. 2, of an overload controlling mechanism generally designated 18. The outlet 20, Fig. 2, of the mechanism 18 is directly connected to the inlet port of the compressor 1. A suitable source of rotative energy such as the electric motor 22 may be connected as by means of a belt 24 for driving the compressor 1.

The motor 22 is controlled in a suitable manner such as a thermostat generally designated 26 and embodying an on-and-off switch (not shown) for making and breaking current in one or both of the lines L1 and L2. The thermostat 26 embodies a temperature sensitive element 28 which is located within the space 12 to be cooled and operates in the usual manner to close the switch contacts in the thermostat 26 upon increase of temperature in the space 12 above that desired and to open the contacts in the thermostat 26 when the temperature in the space 12 falls to a predetermined low limit. It will be apparent that if desired a control such as that shown in my copending application, Serial No. 750,947 filed May 28, 1947, now U. S. Patent No. 2,626,506, for Control Mechanism, could be used to vary the rate of speed of the motor 22 instead of merely turning it on and off whereby the temperature within the refrigerated space might be maintained within predetermined limits. It will be obvious that a gasoline engine or other source of prime energy could be used to drive the compressor 1 and the operation of the engine be controlled by a suitable temperature responsive element adapted for use with that particular source of prime energy. Such an element and system is shown in my above-mentioned U. S. Patent No. 2,626,506, and also in my U. S. Patent No. 2,626,507 for Method and Apparatus for Controlling Refrigerating Systems.

The energy required to drive a compressor 1 will be a function of the weight of the fluid being transferred by the compressor per unit of time and also proportional to the difference in pressure between which the fluid is transferred. As is well known in the refrigeration art, when the temperature of the evaporator 10 is higher than normal, the refrigerant pressure therein increases and more power is required to drive the compressor. If the driving mechanism, such as the motor 22, were selected so that there would be sufficient power to drive the compressor 1 at all pressure conditions imposed thereon then when the compressor 1 is operating with normal pressures in the evaporator 10 and the condenser 2, the motor would be partially loaded and would not operate as efficiently as a more nearly fully loaded motor. Also the cost of the larger size motor would make its use uneconomical. The control 18, placed in the suction line 14 and in communication with the inlet port to the compressor 1, regulates the pressure at the compressor inlet and consequently the weight of fluid being pumped by the compressor to prevent such weight from becoming excessive and more than the motor 22 is capable of pumping.

The apparatus 18 comprises generally a housing member 30 having a fluid flow passageway 32 leading from the inlet 16 and opening into the outlet 20. In this passage is arranged a valve member 34 which may be of the balance butterfly type as shown pivoted upon a shaft 36 extending transversely across the passageway 32. It will be apparent that the flow capacity from the inlet 16 to the outlet 20 through the passageway 32 is determined to a great extent by the rotative position of the butterfly valve 34. That is, when the valve 34 is in the position

as shown, maximum fluid can flow through the passageway 32 while when the valve has been rotated clockwise from the position shown to a substantially closed position, the flow of fluid through the passageway 16 is substantially reduced if not entirely stopped. The positioning of the valve 34 is determined by the resultant of the forces exerted by a piston 38 sensitive to discharge pressure and by the fluid force exerted on a movable disk 40 within the pressure chamber 42. The pressure within the chamber 42 is substantially that which appears at the end of the passageway 32 adjacent the outlet 20, such pressure being communicated thereto through an aperture 43 in the side wall of the passageway 32 and so positioned that it will be on the end of the passageway 32 adjacent the outlet 20 and separated from the inlet 16 by means of the valve 34 as the valve moves toward closed position.

The housing 30 is provided with a hollow boss 44 extending outwardly of the side wall of the passageway 32 coaxially of the aperture 43 and serves as the outer peripheral wall of the chamber 42. The inner wall of the chamber 42 comprises the peripheral surface of a bellows member 46. The member 46 is sealed at one end to an annular plate 48 which abuts the outer end wall of the boss 44 to form an end wall of the chamber 42. The member 46 is sealed at its other end to the disk 40 within the chamber 42 and inwardly of the common wall section 49 between the passageway 32 and the pressure chamber 42. A thrust rod 50 is pivotally secured at one end portion by the pin 52 to the butterfly valve 34 and is secured at its other end to the disk 40 as by means of a screw 51. One end portion of a piston rod 54 is also pivotally secured by the pin 52 to the valve 34 and at its other end portion is made semi-spherical for reception in a mating semi-spherical aperture in the piston 38. The piston 38 is snugly but slidably positioned within a piston chamber 56 which is located in a boss 57 extending outwardly of the passageway 32, and is preferably coaxial with the chamber 42 and aperture 43. The portion of the chamber 56 outwardly of the piston 38 is suitably arranged to be connected by means of conduit 58 to the discharge conduit 2 whereby the discharge pressure of the compressor 1 acts upon the piston 38 to urge it in a rightward or inward direction (Fig. 2) in proportion to the discharge pressure of the compressor.

The compressor suction pressure is transmitted through the aperture 43 into the chamber 42 and acts upon the end member 40 of the bellows 46 in a direction to collapse the bellows or move the wall 40 toward the right. In this manner an increase in either or both the suction and discharge pressure of the compressor 1 will exert a force tending to close the valve 34 to reduce the working load on the compressor. A spring 62 is located concentrically within the bellows member 46 and is arranged with its opposite ends abutting the disk 40 and a transverse wall 64 respectively. The force exerted by the spring will determine the pressures necessary in the chambers 56 and 42 for positioning the valve 34 in its various controlling positions. The transverse wall or plate member 64 forms the fixed wall of the expandable-contractable chamber 65 formed within the bellows member 46 and is provided with a fluid flow restricting orifice 66 extending therethrough. A hollow cap 68 is secured to the outer surface of the plate member 64 with its hollow interior or chamber 69 facing the member 64. The cap 68, plate members 64 and 48 are suitably held tightly together and to the end wall of the boss 44 in fluid-tight engagement by means of cap screws or other means (not shown).

The chamber 65 is completely filled and the chamber 69 partially filled with a fluid such as oil. The oil is introduced into the chambers 65 and 69 through an internally threaded aperture 70 in the cap 68 which, after introduction of the oil, is closed as by means of a plug 72, such introduction preferably being made with the axis of the chamber 65 extending in a vertical direction with

the aperture 70 uppermost. The plug 72 has a venting aperture 72a to permit the fluid level therein to vary while still being maintained at atmospheric pressure. The member 64 is provided with a passageway 73 for venting of the chamber 65 during the introduction of the oil after which it is closed by a plug 74. As the movable wall or disk 40 moves back and forth, the volume of the chamber 65 varies and the necessary oil flows through the orifice 66, the restriction to flow through the orifice 66 acting to damp the movement of the movable wall 40 and the butterfly valve member 34 so that the position of the valve member 34 will be substantially proportionate to the average discharge and suction pressure rather than to instantaneous or transient pressures which might appear for various reasons and also prevents a hunting action of the valve.

The position of the valve member 34, as shown in Fig. 2, is that in which the compressor is operating at or below its maximum rated loading. Let us now assume that for some reasons, such as the placing of an article to be refrigerated in the space 12 the pressure within the evaporator 10 increases. This increase of pressure will normally increase the pressure at the inlet of the compressor 1 and a greater weight of refrigerant gas will be pumped per unit of time by the compressor 1. This increase in weight of the gas being pumped by the compressor 1 increases the power required to drive the compressor and also tends to increase the discharge pressure due to the fact that a greater differential in temperature must be maintained between the condenser 3 and the medium to which the added heat is dissipated. This increase in suction pressure passes through the aperture 43 and reacts upon the outer face of the movable wall 40 tending to move the wall to the right. Upon the occurrence of a predetermined combined value of discharge and suction pressures which may be an increase in either or both, the controlling mechanism 18 will start to throttle the flow of suction vapor to the compressor due to movement of the valve 34 toward closed position. This increase in one or both the discharge and suction pressures acts on the piston 56 and the wall 40 tending to urge them toward right to rotate the valve 34 in a clockwise direction restricting the flow of refrigerant vapor from the evaporator 10 to the compressor 1. The relative pressure areas of the piston 56 and wall 40 are chosen to produce an effect corresponding to the relative change in power characteristics of the compressor with change in suction and discharge pressure. The spring 62 is chosen to calibrate the mechanism 18 to the absolute magnitude of pressure so that the throttling effect of the valve 34 to control the quantity of suction gas admitted to the compressor will not permit the compressor to receive a greater weight of refrigerant vapor than that for which the motor 22 is designed. As the evaporator pressure falls the opposite effect will be produced on the apparatus 18 to reduce any restrictive effect of the valve 34.

In Fig. 3 there is shown a modified form of control apparatus 18a which acts to perform a similar function as does the apparatus 18 but is operated by servomotor 60 responsive to the intake and exhaust pressures of the compressor 1. In this form, the intake or suction pressure is applied directly to the chamber 118 while the discharge or exhaust pressure of the compressor 1 is applied to the underside of the valve 134 which slides within the bushing 92. The upper portion of the valve 134 is of larger diameter than the port 136 to provide an annular pressure sensitive area against which the discharge pressure acts to exert a force on the wall 130 proportional to the discharge pressure. The diameter of the port 70 136 may remain constant while the outer diameter of the valve 134 and inner diameter of the bushing 92 may be varied to provide the correct area of annular pressure sensitive area relative to the area of wall 130 for operation of the valve 134 substantially as described in connection with the operation of valve 34.

The apparatus shown in Fig. 3 comprises a pair of hollow housing members 100 and 102. The housing member 100 is provided with an inlet opening 104 adapted to be secured to the suction conduit 14 or equivalent of a refrigerating system whereby the suction gases from the evaporator 10 may be introduced to the interior of the hollow housing member 100. The housing member 100 also has an outlet passageway 106 leading from the hollow interior thereof outwardly of the housing member and is adapted for connection to the intake port of the compressor 1. The housing member 100 is also provided with a piston chamber 108 in which a piston 110 is positioned for movement. The piston 110 has a piston rod 112 at one end of which is carried a valve member 114 which is coactable with a valve seat 116 through which the suction vapors pass from the inlet 104 to the hollow interior of the housing member 100.

The interior of the housing member 102 is open to the hollow interior of the member 100 through a hollow tubular member 122 which is press-fitted or otherwise suitably sealed as by brazing to the body members 100 and 102. A bellows member 124 is positioned within the chamber 118 and is secured at one end to an annular ring 126 which is clamped between a cap member 128 and the body member 102. The other or lower end of the bellows member 124 is closed by means of a movable wall or disk 130 so that a pressure chamber 118 is formed exteriorly of the bellows 124. The interior of the bellows 124 is open to atmosphere through bleed passageway 131 in the cap member 128. A controlling member such as needle valve 134 is actuated by the wall 130 and coacts with valve port 136 to control flow of high pressure refrigerant vapor from an inlet 138 to an outlet conduit 140 for providing the necessary energy to actuate the valve 114. A tubular member 141 is carried by the cap member 128 and serves as a stop to limit upward movement of the end member 130. The usual helical coil spring 142 is arranged interiorly of and concentric with the bellows 124 and seats at one end against the cover member 128 and its other end against the inner surface of the movable wall 130. It will now be apparent that the valve 134 will be actuated by change in pressure within the housing 100 to control the flow of actuating fluid to actuate the valve 114.

The piston rod 112 associated with the valve 114 is provided with an internal bore 146 which fits over a guide member 148 carried by the housing member 100 whereby the piston rod 112 and valve 114 will be guided for vertical movement. In order that there may be no fluid pocket within the bore 146 to interfere with free movement of the valve 114 in accordance with change in pressure across the piston 110, the piston rod 112 is provided with a venting passageway 150 opening outwardly through the piston rod 112 into the hollow interior of the housing 100. The piston 110 is provided with a controlled or restricted fluid flow port 152 for a purpose which will be made clear presently.

It is believed that it will be obvious from the discussion of the operation of the apparatus of Fig. 2 that as the suction pressure of the compressor increases such increase in pressure will be transmitted through the passageway 120 formed by the hollow interior of the member 122 into the chamber 118. Such increase in pressure causes the movable wall 130 to move upwardly thereby moving the needle valve 134 upwardly. Likewise an increase in discharge pressure causes the valve 134 to exert an increased upward force on the wall 130 for moving the wall upwardly. Such upward movement of the valve 134 permits an increase in fluid flow from the high pressure fluid source through the conduit 140 to the underside of the piston 110. Such flow of fluid through the conduit 140 will increase the pressure in the chamber 154 proportionately to the amount of opening of the valve port 136. Such increase in pressure in the chamber 154 causes the piston 110 to move upwardly thereby moving the

valve member 114 closer to the valve seat 116 for restricting flow of fluid from the evaporator 8 to the compressor 1 so that the suction pressure of the compressor 1 does not rise beyond the desired value. Conversely, as the suction pressure and/or discharge pressure decreases, the pressure in the chamber 118, external of the bellows 124, decreases permitting the spring 144 to move the wall 130 downwardly thereby moving the needle valve 134 closer to its seat 136 and lowering the flow of fluid to the conduit 140 to the chamber 154 thereby lowering the pressure in the chamber 154 permitting the valve member 114 to move downwardly away from the valve seat 116 for decreasing the restriction to fluid flow through the casing 100. The flow capacity of the passageway 152 is sufficiently small with respect to that of the port 136 so that a pressure differential of varying magnitude across the piston 110 will be established by the varying position of the valve 134.

The refrigerating apparatus of Fig. 4 is similar to that of Fig. 1 in that it comprises a compressor 1, a condenser 3, a receiver 4, a liquid line 6, an expansion valve 8, an evaporator 10 located in the space 12 which is to be refrigerated, a suction line or conduit 14 and a discharge conduit 2. In this form of the invention the motor 22 or other source of prime mover is continually energized whereby the compressor is operated continually. The pumping capacity of the compressor however is varied under the actuation of the control mechanism 200 (shown in Figs. 4 and 6) and takes the place of the on-off thermostat 26 used in the system of Fig. 1. The mechanism 200 as used in Fig. 4 is connected to supply controlled amounts of high pressure refrigerant vapor from the receiver 4 through the conduit 222 to the fluid chamber 154 of the control mechanism 18a whereby the position of the valve member 114 relative to its seat 116 may be controlled as a function of the pressure in the evaporator 10 to maintain a desired temperature in the space 12. In this regard it will be noted that the control of the mechanism 18a by the mechanism 200 will not interfere with the before described operation of the mechanism 18a by the control 90 to prevent undue overloading of the driving motor 22 since the overload controlling function occurs at high evaporator pressures and the temperature controlling function occurs at low evaporator pressures in which this motor 22 has ample power to drive the compressor 1. In the system of Fig. 4, there is provided a valve 114 actuated by two controlling devices to perform an evaporator controlling function at low evaporator temperatures and pressures and a compressor controlling function at high compressor power requirements to limit the compressor loading so that the power required thereby does not exceed the power which may safely be delivered by the motor 22.

The mechanism 200 is shown and claimed in my co-pending application Serial No. 74,586 filed February 4, 1949, now U. S. Patent 2,626,507. Essentially the apparatus 200 comprises a pressure sensitive chamber 202 communicatively connected by passageway 204 and conduit 206 to the evaporator 10 whereby the pressure in the chamber 202 is proportional to that in the evaporator. The position of the movable wall 208 will be a function of the pressure within the evaporator 10. The wall 208 moves a controlling valve element 210 whereby fluid flow past the valve seat 212 is controlled as a function of evaporator pressure. High pressure fluid from the receiver 4 is conveyed by means of conduit 214 to the inlet 216 of the apparatus 200 which is in open communication with one side of the valve seat 212. Fluid passing through the seat 212 flows into the chamber 218 which has an outlet 220 communicatively connected by means of conduit 222, Fig. 5, to an inlet 224 opening into the chamber 154 and which was shown plugged in Fig. 3. When plugged, the mechanism 18a is adapted for use as above described in the system of Fig. 1. When the inlet 224 is connected with conduit 222 as shown in Fig. 5, the

mechanism is suited for use in the system of Fig. 4. A control knob 226 of the apparatus 200 is rotated so that the spring 228 will oppose upward movement of the movable wall 208 sufficiently so that the valve member 210 will be positioned relative to the valve port 212 at the desired evaporator pressure to regulate the flow of the high pressure fluid to the chamber 154 to cause the valve member 114, Fig. 3, to be positioned relative to its seat 116 to restrict flow of fluid from the evaporator 10 to the compressor 1. This position is such as to permit just sufficient fluid flow from the evaporator 10 to the compressor 1 to maintain the desired pressure in the evaporator 10 irrespective of the fact that the compressor 1 has a tendency to lower this pressure below the desired limit.

The control 200 may be used with or without the overload servomotor 90 shown in Fig. 3. If used without the overload servomotor 90, the conduit 149 may be removed and the opening into which the conduit 140 was connected may be closed as by a plug. Under these conditions an increase in evaporator pressure reduces fluid flow through the port 212 thereby reducing the pressure differential across the piston 110 permitting the valve 114 to move further away from its seat 116. If both the servomotor 90 and control 200 are used in combination to supply fluid to the chamber 154, the valve member 114, during periods when the evaporator pressure is such as to cause overloading of the motor 22, is positioned relative to its seat 116 to restrict the inlet pressure of the compressor 1 to a value such as to prevent undesired overloading of the motor 22 as described it being realized at this time that the valve 210 will prevent fluid flow through the port 212 and the conduit 222 is effectively plugged and the valve member 114 is controlled by the valve 136. As the evaporator and/or condensing pressures are reduced into the range which will not cause undesired overloading of the motor 22, the valve 134 will plug the port 136 and conduit 140 is in effect plugged calling for full open position of the valve member 114. As the evaporator pressure tends to be lowered below the desired pressure, the valve member 114 again throttles fluid flow and is regulated by the control 200. The reduction in pressure in the evaporator is transmitted to the chamber 202 causing the valve 210 to open the port 212 for fluid flow to the chamber 154 for movement of the piston 110 and valve 114 upwardly whereby fluid flow through the port 116 is reduced to the vapor withdrawing effect of the compressor 1 on the evaporator 10.

If desired unidirectional fluid flow valves 230 may be placed in either or both of the conduits 140 and 222 to insure that there is no reverse fluid flow therethrough. It will thus be evident that in the form of the invention disclosed in Figs. 4, 5 and 6, the refrigerating system acts to prevent undesired overloading of the motor 22 and further permits continued operation thereof without causing an undesired low temperature of the evaporator 10 and space 12.

In the modification shown in Figs. 7 and 8, there is shown a gasoline engine 22a having a governor 250 for controlling the speed of operation thereof between predetermined limits and which also includes the regulator 200 for controlling the refrigeration effect of the compressor 1 and the load limiting features as shown in Figs. 1 and 4. This governor is controlled by a piston cylinder combination 252 shown connected in the system in Fig. 7 and in detail in Fig. 8 and more completely disclosed in my said copending application Serial No. 74,586. In this form the control mechanism 18a is actuated at high compressor power requirements to control the valve member 114 relative to the seat 116 to prevent the power requirements of the compressor from exceeding the power which may safely be delivered by the engine 22a in a manner similar to that described above under control of the servomotor 90. The mechanism 200 upon a reduction in the temperature of space 12 as reflected by a reduction in evaporator temperature to first actuate the governor con-

trolling combination or device 252 to reduce the speed of the engine 22a to lower the pumping capacity of the compressor 1 to prevent an undesired reduction in temperature of the space 12. Since engines, and especially air cooled engines, do not perform well below a minimum speed it is not desirable to continue to reduce the speed below this minimum speed. In many instances this minimum speed results in driving the compressor at a speed in which it reduces the temperature of the evaporator 10 sufficiently to reduce the temperature of the space 12 below that desired. Under these conditions the mechanism 200 often reduces the engine speed to the minimum speed then actuates the mechanism 18a to move the valve member 114 toward the valve seat 116 to throttle the flow of suction vapor from the evaporator to the compressor. The system of Fig. 7 therefore provides a continuously operating refrigerating system which is prevented from overloading the engine by throttling of the suction vapor and prevented from reducing the temperature of the space 12 below a desired temperature by reducing the engine speed to reduce the capacity of the compressor and by throttling the suction vapor to the compressor to further reduce the capacity of the compressor. The combination 252 has a fluid inlet 254 which is connected as by means of branch conduit 256 to the conduit 222 whereby it is under control of the apparatus 200 shown in Fig. 6. The apparatus 200 also acts to control the valve 114 as described in connection with the system of Fig. 4. The inlet 254 opens into a chamber 258 closed at its upper end by a piston 260 having a restricted fluid flow passageway 262 therethrough and opening into a chamber 264 above the piston 260. The chamber 264 has an outlet 266 connected by means of conduit 268 directly to the inlet of the compressor 1 whereby the chamber 264 is maintained at all times substantially at the inlet pressure to the compressor 1. A piston rod 270 of the piston 260 extends outwardly of the combination 252 for connection with the governor 250. The chamber 254 is suitably sealed against loss of fluid to or reception of fluid from the ambient air by means of bellows 272.

It is believed that it will be apparent from the foregoing that as the valve 210 is opened to permit a greater fluid flow through the port 212, as described above, fluid will pass through conduits 222 and 256 to the chamber 258 causing a pressure increase in the chamber 258 and a movement of the piston 260 and rod 270 downwardly to move the throttle toward closed position to decrease the compressor speed. Movement of the piston 260 downwardly may be limited by a cylindrical stop 274 or the throttle movement under control of the piston 260 toward closed position may be limited by any other suitable means whereby the minimum operating speed of the engine 22a may be predetermined. By such a combination, the engine 55 may be operated continuously within a speed range which permits of sufficient cooling by the fan 276 with which engines of the type customarily used for these applications are equipped, prevents the evaporator 10 and space 12 from being cooled below the desired temperatures, and to 60 utilize the savings in fuel which are present with reduced speed operation.

What is claimed and is desired to be secured by United States Letters Patent is as follows:

1. In a refrigerating system, a compressor having an inlet and an outlet, an evaporator connected to receive refrigerant from said compressor and having an outlet, a suction vapor passageway connecting said evaporator outlet to said compressor inlet, a valve in said suction passageway for controlling fluid flow therethrough and a pair of valve actuators operatively inter-connected to said valve to actuate said valve toward a closed position as a result of the interaction of the effects of said actuators, a first of said actuators being responsive to an operating condition of said evaporator to urge said valve toward a closed 75 position in response to a first magnitude of said evaporator

condition, a second of said pair of actuators being responsive to an operating condition of said compressor to urge said valve toward a closed position in response to a first magnitude of said compressor condition, a means for driving said compressor at a reduced speed, and means operatively connecting said first actuator to said driving means rendering said first actuator effective to control said driving means to reduce the speed at which said compressor is driven in response to a second magnitude of said evaporator condition.

2. In a refrigerating system, a compressor having an inlet and an outlet, an evaporator connected to receive refrigerant from said compressor and having an outlet, a suction vapor passageway connecting said evaporator outlet to said compressor inlet, a valve in said suction passageway for controlling fluid flow therethrough and a pair of valve actuators operatively inter-connected to said valve to actuate said valve toward a closed position as a result of the interaction of the effects of said actuators, a first of said actuators being responsive to an operating condition of said evaporator to urge said valve toward a closed position in response to a first magnitude of said evaporator condition, a second of said pair of actuators being responsive to an operating condition of said compressor to urge said valve toward a closed position in response to a first magnitude of said compressor condition, means having a variable power output for driving said compressor, and means operatively connecting one of said actuators to said variable power means rendering said one actuator effective to control said variable power means in response to a second magnitude of the condition to which it is responsive.

3. In a refrigeration system, a compressor, an evaporator, fluid flow means interconnecting said compressor and said evaporator for providing a regulated flow of fluid from said compressor to said evaporator, a fluid flow means interconnecting said compressor and said evaporator for providing a fluid flow path from said evaporator to said compressor, means including a flow-restricting device in said last-named fluid flow means, a fluid-powered operating means for said device, and a speed control means for regulating the rate at which said compressor operates, a pair of actuators for supplying actuating fluid to said fluid-powered operating means and said speed control, means rendering the operation of a first of said actuators responsive to an increase in the work done by said compressor causing it to supply operating fluid to said fluid-powered operating means to cause said flow-restricting device to reduce the rate of removal of fluid from said evaporator, means rendering a second of said actuators responsive to a decrease in pressure in said evaporator causing said actuator to supply fluid to said speed control means causing the latter to reduce the speed of said compressor and to said fluid-powered operating means to cause said flow-restricting device to reduce the flow of fluid from said evaporator to said compressor, and means rendering said speed control means ineffective to reduce the speed of said compressor below a predetermined minimum.

4. In a refrigerating system, a compressor having an inlet and an outlet, an evaporator having an inlet and an outlet, a first fluid flow passageway interconnecting said compressor outlet and said evaporator inlet and providing a regulated flow of fluid from said compressor to said evaporator, a second fluid flow passageway interconnecting said compressor inlet and said evaporator outlet for providing a fluid flow path from said evaporator to said compressor, a third fluid flow passageway communicatively connecting said compressor outlet and inlet in by-pass relation to said evaporator and including means restricting fluid flow therethrough, a first flow controlling element in said third passageway intermediate said third passageway restricting means and said compressor outlet and controlling fluid flow therethrough, a second flow controlling element controlling fluid flow through said second passageway, a pressure sensitive element connected to respond to the pressure in said third passageway intermediate its

said restricting means and said first flow controlling element and having a pressure responsive portion operatively connected to said second flow element for actuation thereof, a pair of pressure sensitive elements operatively connected for actuation of said first flow controlling element and operable upon increase in pressure to actuate said first flow element to open position, one of said actuators being responsive to the pressure of the fluid in said compressor outlet, and the other of said actuators being responsive to the pressure of the fluid in said compressor inlet.

5. In a refrigerating system, a compressor having an inlet and an outlet, an evaporator having an inlet and an outlet, a first fluid flow passageway interconnecting said compressor outlet and said evaporator inlet and providing a regulated flow of fluid from said compressor to said evaporator, a second fluid flow passageway interconnecting said compressor inlet and said evaporator outlet for providing a fluid flow path from said evaporator to said compressor, a third fluid flow passageway communicatively connecting said compressor outlet and inlet in by-pass relation to said evaporator and including means restricting fluid flow therethrough, a first flow controlling element in said third passageway intermediate said third passageway restricting means and said compressor outlet and controlling fluid flow therethrough, a second flow controlling element in said passageway in by-pass relation to said first element and controlling fluid flow through said third passageway, a pressure sensitive element connected to respond to the pressure in said third passageway intermediate its said restricting means and said flow controlling elements and having a pressure responsive portion, means regulating the rate at which said compressor is operable to remove refrigerant from said evaporator and operatively connected to said pressure responsive portion for actuation thereby, a pair of sensitive actuating elements operatively connected to said flow controlling elements for control thereof, means rendering one of said actuators responsive to an operating condition of said compressor, and means rendering the other of said actuators responsive to an operating condition of said evaporator.

6. In a refrigerating system, a compressor, an evaporator, a liquid refrigerant passageway including a liquid flow controlling means interconnecting said compressor with said evaporator for supplying a regulated flow of liquid refrigerant to said evaporator, a suction refrigerant passageway including a suction fluid flow regulator interconnecting said evaporator with said compressor for supplying a regulated flow of suction refrigerant to said compressor, a fluid-powered operating means for said suction fluid flow regulator, a first actuating device responsive to a minimum operating condition of said evaporator and having a controlling element operatively connected to said fluid-powered operating means to supply operating fluid to the latter causing it to operate said suction flow regulator to reduce the flow of refrigerant to said compressor, a second actuating device responsive to maximum operating conditions of said compressor and having a single controlling element adapted to supply operating fluid to said fluid-powered operating means to cause the latter to reduce the rate of flow of suction refrigerant to said compressor, said last-named single controlling element having two pressure sensitive elements each having a pressure responsive portion, fluid flow means operatively connecting said last-named single control element with said fluid-powered operating means, pressure conveying means connecting one of said pressure sensitive elements to respond to the intake pressure of said compressor, and pressure conveying means connecting the other of said pressure sensitive elements to respond to the outlet pressure of said compressor.

7. In a refrigerating system, a compressor, an evaporator, a liquid refrigerant passageway interconnecting said compressor and said evaporator for providing a regulated flow of liquid refrigerant from said compressor to

said evaporator, a suction conduit interconnecting said compressor and said evaporator for providing a fluid flow path from said evaporator to said compressor, a valve regulating the flow of suction refrigerant through said suction conduit to regulate the rate at which suction refrigerant is removed from said evaporator by said compressor independently of the rate at which liquid refrigerant is supplied to said evaporator by said liquid flow regulating means, a first actuator operatively connected to control said valve, means rendering said first actuator responsive to an increase in the work done by said compressor to move said valve toward closed position to reduce the suction refrigerant admitted to said compressor, means controlling the speed at which said compressor is driven, a second actuator responsive to an operating condition of said evaporator, and means rendering said second actuator responsive to a decrease in the magnitude of said evaporator condition to actuate said compressor speed controlling means to reduce the speed at which said compressor is driven.
